D 19540

UNITED STATES PATENT OFFICE.

JOSEPH BUDDE, OF SAN FRANCISCO, CALIFORNIA.

DESIGN FOR A WATER-CLOSET BOWL OR STAND.

SPECIFICATION forming part of Design No. 19,540, dated December 31, 1889.

Application filed November 22, 1889. Serial No. 331,260. Term of patent 7 years.

To all whom it may concern:

Be it known that I, JOSEPH BUDDE, a citizen of the United States, residing at the city and county of San Francisco, State of California, have invented and produced a certain new and original Design for Water-Closet Bowls, of which the following is a full specification, reference being had to the accompanying photograph, forming a part thereof.

My design relates more particularly to the surface ornamentation, designed to represent the earlier days of California—that is, so to speak, the pioneer days of '49.

My design relates not only to the closet-bowl, but as well to such closets wherein the bowl and stand form the entire closet.

The upper edge of the bowl is formed with the projecting lip A, below which is the surrounding dado B. The letter C indicates the middle or dividing dado of the bowl and stand C', and between this and the upper dado is the surface ornamentation, which represents a wagon-train crossing the plains, to the rear of which are the outlines of the mountains and is to be seen the sun sinking below the horizon. To one side, in front of this representation, upon the cliffs of the rocks is seen the grizzly bear. Below the central dado

is represented the miner at work with his pick, while at a short distance therefrom is to be seen his camp, thereby indicating the early workers of California.

Having thus fully described my design, what I wish to secure protection in by Design Letters Patent is—

1. In a design for water-closet bowls herein shown and described, the upper and central dado surrounding the same, the surface therebetween being decorated by the scene of a wagon-train crossing the plains and of the miner and camping scene below the central dado.

2. As a new design, a water-closet bowl or stand herein shown and described, provided with an upper surrounding lip, an upper dado beneath the same, and the central dado dividing the bowl and stand, the surface therebetween being embossed and decorated to represent the early pioneer days, as set forth.

In testimony whereof I affix my signature in presence of witnesses.

JOSEPH BUDDE.

Witnesses:

N. A. ACKER,
M. G. LOEFLER.
